UNITED STATES PATENT OFFICE

2,053,775

RAILWAY SIGNALING SYSTEM

Daniel J. McCarthy, Elgin, Ill., assignor to Associated Electric Laboratories, Inc., Chicago, Ill., a corporation of Delaware

Application May 23, 1934, Serial No. 727,025

7 Claims. (Cl. 246—87)

The present invention relates in general to railway signaling and more particularly to automatic railway crossing protection.

The main object of the present invention is to provide reliable and inexpensive means whereby the speed of a train between two given points determines whether or not a signal is to be operated.

Another object of the present invention is the provision of means controlled by a train reaching a predetermined point for operating signaling means located at a crossing to give a danger indication in case the speed of the approaching train exceeds a predetermined speed.

Another object of this invention, in conjunction with the above main object, is to provide means whereby the signaling means at the crossing gives a clear indication in case the speed of the train is less than said predetermined speed.

In the present invention, the circuit arrangements are such that the speed of a train between two predetermined points determines whether or not a signal is to be operated and may be used for both railroad grade crossings and highway crossings or at other points where it is desired to limit the speed of trains. In the present embodiment of the invention the circuits are so arranged that unless the speed of the train between the two given points is limited to the proper speed or less the signal at a railroad intersection will be automatically set against the train. In case, however, the train passes between said two given points at the properly reduced speed from a safety standpoint, the crossing signal indicates clear and permits the train to enter the intersection. Therefore, in order to get a clear indication from the signal, the speed of the train must be within certain limits while passing between two given points.

In a co-pending application executed by me of even date herewith, Serial No. 727,026, filed May 23, 1934, I have shown the fundamental principles of the present invention used for controlling the operation of a highway crossing signal which is used to warn highway traffic of an approaching train. In the co-pending application the highway signal is operated by the approaching train from one given point in case the speed of the train exceeds a predetermined speed and is operated by the train from another given point in case the speed of the train is less than said predetermined speed so that the operating time of the signal, or the warning time for the highway traffic, before the train actually reaches the highway crossing, is the same for both fast and

slowly approaching trains. The co-pending application contains the narrow claims directed to the specific disclosures therein, while the instant application contains the broader claims directed to the operation of signals dependent upon the speed of the train.

Referring now to the drawing, T represents the two rails of a railroad track on which trains approach a railroad grade intersection or crossing (not shown) in the direction indicated by the arrow. 2 indicates a signal placed a predetermined distance from the crossing, and 3 indicates the signal located at the intersection or crossing. Along the inside of one of the rails are placed contactors for controlling circuit controlling contacts 4, 5, 6, and 7. These contactors may be substantially of the same design and operation as disclosed in the application of H. F. Obergfell and G. W. Eickenberg, Serial No. 639,558, filed October 26, 1932, wherein the plunger is operated by the train wheels to cause the operation of the circuit controlling contacts in the associated housing. The corresponding circuit controlling contacts in the present drawing are indicated at 4, 5, 6, and 7 wherein such contacts are operated by the associated plungers represented by small circles placed on the inside of the lower rail. Contacts 4 are placed along the track a short distance from signal 2, while the contacts 5 are placed along the track a predetermined distance from contacts 4. The contacts 4 and 5 are separated a definite distance dependent upon the operating time of the slow-acting device, in this case a chain of slow-releasing relays 10 and 12, so that it may be determined when the speed of a train passing between contacts 4 and 5 exceeds a predetermined speed. Contacts 6 and 7 are placed close to the crossing in order to reset the signaling and timing means when the train is proceeding across the crossing. The contactor contacts control circuits of a number of relays, two of which are of the slow-releasing type having copper slugs on their armature ends, as indicated by the cross-hatched sections thereof. 9, 11, and 27 designate batteries for controlling the operation of the relays and crossing signal 3. The relays and signals are shown in their normal condition wherein relays 8, 10, 12, 24, and 25 are normally energized, the signal 2 is set at caution, and the crossing signal 3 is set at clear. Signal 3 is maintained in clear position over a circuit including armature 26 and battery 27. Relay 25 is held energized over a circuit including armature 23 and battery 17. Relay 24 is maintained energized over the following stick circuit: From

one pole of battery 17, conductor 22, winding of relay 24, conductor 30, stick armature 21, conductors 20 and 19, contacts 5, and conductor 18 to the other pole of battery 17. Relay 8 is maintained energized over the following stick circuit: From one pole of battery 9, contacts 4, conductor 31, winding of relay 8, conductor 32, and lower stick armature of relay 8 to the other pole of battery 9. Relay 10 is held energized over a circuit including armature 11 of relay 8 and battery 9. Relay 12 is held energized over a circuit including armature 13 of relay 10 and battery 9. If desired, additional slow-releasing relays may be added in this chain circuit to increase the release time before the last of the slow-releasing relays closes the circuit for relay 15 as a result of the deenergization of relay 8. The operation is as follows: When a train approaches caution signal 2 in the direction indicated by the arrow, the engineer reduces the speed in accordance therewith. Shortly after passing the caution signal 2 contacts 4 are operated by the wheels of the train, thereby opening the previously traced stick circuit for relay 8, whereupon relay 8 deenergizes. At its lower armature relay 8 opens a further point in its stick circuit to prevent its reenergization when contacts 4 close and at armature 11 opens the circuit of the first slow-releasing relay 10. After an interval slow-releasing relay 10 deenergizes and at armature 13 opens the circuit to the next slow-releasing relay in the chain, which in this case is the last relay in the chain or relay 12. After an interval, dependent upon its slow-releasing characteristics, slow-releasing relay 12 deenergizes and at armature 14 completes a circuit for energizing relay 15. As previously stated, by the addition of more slow-releasing relays in the chain circuit the energization of relay 15 may be delayed in accordance therewith. The circuit for energizing relay 15 may be traced as follows: From one pole of battery 9, winding of relay 15, armature 14, to the other pole of battery 9. At armature 16 relay 15 closes a shunt circuit around contacts 5.

The operation from this point on is different dependent upon whether the speed of the train exceeds a predetermined speed or not. That is, the operation is different dependent upon whether contacts 5 are operated by the train before relay 15 closes the shunt circuit around contacts 5 or dependent upon whether the contacts 5 are operated by the train after relay 15 closes the shunt circuit around contacts 5. Assuming first that relay 15 at armature 16 closes the shunt circuit around contacts 5 before the train operates contacts 5, then the operation of contacts 5 by the train is without effect since the stick circuit for signal control relay 24 now includes armature 16. Under this condition relays 24 and 25 are maintained energized and the crossing signal 3 is maintained at clear or proceed position to indicate that the train may proceed, it being understood that signal 3 will indicate clear only in case the track is in clear condition. As the train proceeds past signal 3 contacts 6 and 7 are closed. The closure of contacts 6 is without effect at this time because the signal 3 did not change but the closure of contacts 7 completes a circuit for resetting or reenergizing relay 8 as follows: From one pole of battery 9 by way of conductor 35, conductor 34, contacts 7, conductor 33, conductor 32, winding of relay 8, conductor 31 and contacts 4 to the other pole of battery 9. Relay 8 energizes over the above-traced circuit and at its lower armature completes its previously traced stick

circuit. At armature 11 relay 8, upon energizing, completes the circuit for energizing relay 10. Relay 10, upon energizing, at armature 13 completes the circuit for energizing the next, in this case the last, relay or relay 12 in the chain circuit. At armature 14 relay 12 opens the circuit to relay 15 which thereupon deenergizes to remove the shunt circuit from around contacts 5 by opening contacts 16. The relays 8, 10, 12, and 15 are now reset to their normal positions in readiness for the next approaching train.

It will now be assumed that the engineer on the approaching train ignores the caution signal 2 and does not properly reduce the speed of the train. Relays 8, 10, 12, and 15 operate in the same manner as previously described in response to the train operating contacts 4. In this case, however, the speed of the train is such that contacts 5 are operated by the train before relay 15 is operated and contacts 16 are closed. Since contacts 5 are opened before armature 16 is operated, the stick circuit of signal control relay 24 is opened with the result that such relay deenergizes. At armature 21 relay 24 opens a further point in its stick circuit to prevent its reenergization in response to the intermittent operation of contact 5 by the train passing thereover. At armature 23 relay 24 opens the circuit of signal relay 25, whereupon the latter relay deenergizes. At armature 26 relay 25 opens the circuit to signal 3, whereupon signal 3 is operated to the stop or danger condition in the well-known manner. From the foregoing, it will be seen that if the speed of a train is not reduced to the proper speed, the crossing signal 3 is set against the train regardless of track conditions. The crossing signals 3 may be so arranged that the same is held at danger until released by a dispatcher.

Relays 8, 10, 12, and 15 are reset in the manner previously described in response to the train closing contacts 7. In response to the closure of contacts 6 as a result of the train passing signal 3 the following circuit is completed for energizing relay 24: From one pole of battery 17, conductor 22, winding of relay 24, conductor 28, contacts 6 now closed, conductor 29, contacts 5 now closed, and conductor 18 to the other pole of battery 17. At armature 21 relay 24 completes its previously traced stick circuit and at armature 23 completes the circuit for energizing relay 25. At armature 26 relay 25 again completes the circuit for crossing signal 3, whereupon signal 3 is operated to clear or proceed position in the well-known manner. All of the apparatus has now been reset in readiness for the next train.

From the foregoing it will be seen that a reliable and inexpensive arrangement has been provided for checking an engineman as to his observance of the rule regarding reduced speed when approaching speed restricted zones without installing expensive train stop or train control equipment.

Another precautionary measure has been taken by having the circuit operate on what is known as a closed circuit so that any failure of battery 9 will cause signal 3 to be set at danger regardless of the speed of the train. In case battery 9 fails for some reason, then relay 15 cannot energize to place a shunt circuit around contacts 5 as would be the case on battery failure if contacts 14 instead of contacts 16 closed such shunt circuit. Therefore, in case of failure of battery 9, the shunt circuit around contacts 15 is not

completed with the result that the signal 3 is set against the train regardless of its speed in response to the operation of contacts 5.

It will be understood that while only one track 5 with traffic in one direction has been illustrated, a similar arrangement is provided for a second track having traffic in the opposite direction. Also the intersecting tracks will be provided with similar arrangements, if desired.

10 Having described the invention and what is considered new and is desired to have protected by Letters Patent is set forth in the following claim.

What is claimed is.

15 1. In combination with a railroad track, signaling means located at a predetermined point along said track for governing the right of way over a grade crossing, said signaling means having proceed and stop positions and normally set 20 in its proceed position, a plurality of track-side contactors mechanically operable by the wheels of trains approaching said predetermined point, circuit controlling contacts mechanically controlled by said contactors when operated, the 25 first one of said contactors to be operated by the approaching train being placed at considerable distance from said predetermined point, the second one of said contactors to be operated by the approaching train being placed at a definite distance from said first contactor, means controlled 30 by the operation of the contacts in the operated first and second contactors for operating said signaling means from its proceed position to its stop position only in case the train travels between said first and second contactors with a speed exceeding a predetermined speed, and means operated in case the speed of the train is less than a predetermined speed between said first and second contactors for maintaining said 35 signaling means in its proceed position during the approach and while the train is passing over said crossing.

2. In combination with a railroad track, signaling means located at a predetermined point along said track for governing the right of way 45 over a grade crossing, said signaling means having proceed and stop positions and normally set in its proceed position, a plurality of track-side contactors operable by trains approaching said predetermined point, circuit controlling contacts 50 controlled by said contactors when operated, the first one of said contactors to be operated by the approaching train being placed at considerable distance from said predetermined point, the second one of said contactors to be operated by the approaching train being placed at a definite distance from said first contactor, slow-acting means 55 controlled by the contacts of said first contactor and initiated in its operation in response to the operation of said first contactor, means for controlling the operation of said signaling means from its proceed position to its stop position, means for operating said last means in response to the operation of the second of said contactors 60 only in case the complete operation of said slow-acting means is incomplete at the time said second contactor is operated, and means controlled by said slow acting means in case the slow acting means is fully operated at the time the said second contactor is operated for maintaining said 65 signaling means in its proceed position while the train is approaching and passing over the crossing.

3. In combination with a railroad track, signaling means located at a predetermined point

along said track for governing the right of way over a grade crossing, said signaling means having proceed and stop positions and normally set in its proceed position, track-side equipment operable by trains approaching said predetermined point, said equipment located along said track at predetermined distances from said predetermined point, means controlled by the operation of said track-side equipment for operating said signaling means from its proceed position to its stop position only in case a train approaches said predetermined point with a speed exceeding a predetermined speed, and means operated in case the speed of the train is less than a predetermined speed for maintaining said signaling means in its proceed position while the train is approaching and passing over said crossing.

4. In a railway signaling system, a plurality of contacts located at predetermined points along the track and operable in succession by an approaching train, a normally energized start relay, a stick circuit for said start relay, said stick circuit opened in response to an approaching train operating the first encountered one of said contacts to release said start relay, a chain of normally energized slow-releasing relays initiated in their releasing operations in response to the operation of said start relay, a normally open shunt circuit around the second of said contacts, means responsive to the release of the last slow releasing relay in the chain for closing said shunt circuit around the said second contacts, a signal controlling relay, a stick circuit for said signal relay including the said second contacts, and means for opening the stick circuit of said signal relay in response to the approaching train operating the said second contacts, said signal relay maintained energized over said shunt circuit in case said shunt circuit is closed before the operation of said second contacts.

5. In a railway signaling system, a plurality of contacts located at predetermined points along the track and operable in succession by an approaching train, a normally energized start relay, a stick circuit for said start relay, said stick circuit opened in response to an approaching train operating the first encountered one of said contacts to release said start relay, a chain of normally energized slow-releasing relays initiated in their releasing operations in response to the operation of said start relay, a normally open shunt circuit around the second of said contacts, means responsive to the release of the last slow releasing relay in the chain for closing said shunt circuit around the said second contacts, a signal controlling relay, a stick circuit for said signal relay including the said second contacts, means for opening the stick circuit of said signal relay in response to the approaching train operating the said second contacts, said signal relay maintained energized over said shunt circuit in case said shunt circuit is closed before the operation of said second contacts, and means controlled by other of said contacts for reenergizing said start relay to complete its stick circuit and reset said chain of relays and for reenergizing said signal controlling relay to complete its stick circuit in case the same has been opened.

6. In a railway signaling system, a plurality of contacts located at predetermined points along the track and operable in succession by an approaching train, a signal normally held in proceed position, a normally energized signal controlling relay for controlling said signal, a stick circuit for said relay including the second of said contacts.

tacts operated by the approaching train, slow-releasing means initiated in response to the approaching train operating the first encountered one of said contacts, means operated by said slow-releasing means when fully operated for shunting the said second contacts after a predetermined time to maintain said stick circuit and said relay energized only in case the said second contacts are operated after the shunt is closed, the operation of said second contacts opening said stick circuit to release said relay only in case said second contacts are operated before said shunt is closed, said signal maintained in its proceed position while the train is approaching and passing over said crossing in case said relay is maintained energized over the shunt stick circuit and said signal being operated from proceed to stop position in case said relay is released, and means controlled by others of said contacts when operated for reenergizing and resetting said slow-releasing means and said signal relay if released.

7. In a railway signaling system, a plurality of contacts located at predetermined points along the track and operable in succession by an approaching train, slow-acting means controlled by the first contacts encountered by an approaching train, means controlled by said slow-acting means for rendering the operation of the second train encountered contacts ineffective for signaling purposes after a predetermined time, signaling means located at a grade crossing normally set at proceed position and operated to stop in response to the operation of the said second contacts only in case the approaching train operates the said second contacts before said slow-acting means operates said last means, said signaling means being maintained in its proceed position while the train is approaching and passing over said crossing in case said last means is fully operated before the train operates said second contacts.
